(57) **CLAIM**

The ornamental design for a gear shift lever, as shown and described.

DESCRIPTION

FIG. 1 is a left, front perspective view of a gear shift lever according to my novel design;

FIG. 2 is a front view thereof;

FIG. 3 is an elevated right, rear perspective view thereof;

FIG. 4 is a left side view thereof;

FIG. 5 is a left, rear perspective view thereof;

FIG. 6 is a right view thereof;

FIG. 7 is an elevated left, rear perspective view thereof; and,

FIG. 8 is a right, front perspective view thereof.

The broken lines are for illustrative purposes only and form no part of the claimed design.
